UNITED STATES PATENT OFFICE.

JERRY E. CAHILL, OF BALTIMORE, MARYLAND.

DESIGN FOR A CASING OF VENDING-MACHINES.

No. 37,968.

Specification for Design.

Patented April 24, 1906.

Application filed March 9, 1906. Serial No. 305,182. Term of patent 7 years.

To all whom it may concern:

Be it known that I, JERRY EDWARD CAHILL, a citizen of the United States, and a resident of Baltimore, in the State of Maryland, have invented and produced a new and ornamental Design for a Casing for Vending-Machines.

In the accompanying drawings, Figure 1 is a perspective view, and Fig. 2 a rear view, of an animal figure embodying my design.

What I claim is—

The ornamental design for casing of a vending-machine as shown.

JERRY E. CAHILL.
